Term of patent 14 years

Int. Cl. D12—15

U.S. Cl. D90—20

FIG. 1

FIG. 2

FIG. 3

FIG. 1 is a perspective view of a tire showing my new tread design in only a portion of the circumference of the tire between lines X and Y, it being understood that the full line portion of the tread pattern design shown is repeated throughout the circumference of the tire;

FIG. 2 is an enlarged fragmentary plan view of the portion of my new tread design shown between lines X and Y of FIG. 1;

FIG. 3 is a cross-sectional view taken substantially on line 3—3 of FIG. 2.

The characteristic features of my design reside in the tread and shoulder designs which are illustrated in FIG. 2.

I claim:

The ornamental design for a tire, substantially as shown and described.
